CLAIM

The ornamental design for a combined dispensing closure and overcap, substantially as shown and described.

DESCRIPTION

FIG. 1 is a side elevational view of a combined dispensing closure and overcap showing my new design;
 FIG. 2 is a side elevational view of the overcap portion;
 FIG. 3 is a side elevational view of the dispensing closure;

FIG. 4 is a top plan view thereof;
 FIG. 5 is a bottom plan view thereof;
 FIG. 6 is a top plan view of the overcap portion;
 FIG. 7 is a bottom plan view thereof; and
 FIG. 8 is an enlarged sectional view taken along line 8—8 of FIG. 1.
